*E. Thomas,
Fracture Apparatus,*

Patented Mar. 8, 1836.

Mar 8, 1836

C. Crook Thomas - Athens, Ohio
Letters Patent.

In the Schedule and Drawing annexed to the Letters Patent and making part of the same, containing a description of the words of the said Crook Thomas himself of his improvement in the Metallic Walking Splint, for reducing fractures & dislocations.

I, C. Crook Thomas, of the town of Athens in the County of Harrison and State of Ohio, have invented a new and useful improvement in the Splint for reducing fractures and dislocations of limbs in the human frame, called "Thomas' Metallic Walking Splint." Which is described as follows:—
 inasmuch as to the annexed drawings of the same making part of this specification, this splint is adapted to the leg of any person of height from five feet to seven feet, also to any person ligamentous or otherwise. The reduction of the fracture or dislocation being accomplished by the use and power of Springs. According to these annexed drawings the principles of this splint, reference must be had to the annexed drawings, all being to be read in conjunction with the following description:—
 1. The part above the knee to consist of two parts, 1. The knee A. A. 2. The part below the knee, &c. B. The part above the knee to consist of the following parts:—
 3. The parts are connected by screws and springs. The knee is connected with the part below the knee by the screw K. R. which passes through the metal and slides in the hole of the other. Two lateral rods are fastened to the shoulder of screw B. in each splint. In the lower end of the splint K. R. there is a wide 1/8 inches long slot the bottom of which is a shoulder at the which the screw K. R. passes. The lateral rods A. have a slot through them to a groove in the screw K. R. by which the rod is kept in its place. This can also be effected by running a nail on the rod close to the shoulder A. so that by moving the same it will act on the splint at B. Side view by passing the screw K. R. the splint below the knee can be lengthened or shortened, &c. or more easily by which a fracture below the knee may be reduced with great ease. The short band C. before the knee to which the splint are attached by means of the hinge. It is the point of reduction in reducing the any one of the arms may be taken out, while the other two remain in full force so that they can be drawn off. The foot is a curved foot in the shape of the straight A. which passes over the instep from a straight to a curved line; first of the heel, as will be seen in the right and straight on the other side.

In another strap C from the quarter, with a buckle. It is fastened by the cap with a strap and buckles D D D. The part below the knee is connected to the part above the knee by a hinge (fig 8.) and this is a splint fig 9 which gives flexion to the splint when it covers the steel bands D D D. on the hand above the knee and shoulders fig 12. which answers to the shoulder of the slide in the splint. Then which answers to the shoulder of the slide, the screw E of the thigh comes to the shoulder arm S. this which it passes as in the splint below the knee. The slide in these splint in the knee as above below fig 11 $\frac{1}{2}$ inches which together give to the splint 15 inches more than its natural length. The last screw E on the knee as in the lower splint, which also must be fastened by a nut on the end K. instead of the screw K. secured on to the end close to and above the shoulder N. C. and of the steel bands D D D passes through a screw in the other D D. inches so that the bands can be enlarged or diminished when required. These bands in the application of the splint are to be laid open. when the leg is in the bands are fastened by the last screw E. so that any leg, natural or deformed may be accommodated, and by the slide and cap screws in the knee & the whole splint may be enlarged from top to the bottom. In the application of this splint the knee is first put on and secured; then the bands are opened and the leg laid in and secured by the last screw. Then the splints are brought in and the screws below the knee fastened in place by the last screw belonging to them or by a nut secured on the end above the shoulder N. Then by rolling on the knee the leg is extended. Rolling about the knee and in the same manner. The illiumpubic is then put on and the straps buckled around the same part of the abdomen and they may be enlarged at pleasure. All the splints ^{any part can be buckled} as well as the bands and illiumpubic are padded. See a pic. for illustration of my invention. I refer to the model of the same deposited in the Patent Office. What I claim as my invention and which I desire to secure by letters patent is the combination arrangement and adaptation of the several parts of the splint as before described, for the reduction of fractures and dislocation of bones.
